UNITED STATES PATENT OFFICE.

MARION E. WATTS, OF PORTLAND, OREGON.

EXCAVATOR.

1,199,844.

Specification of Letters Patent. Patented Oct. 3, 1916.

Application filed October 18, 1915. Serial No. 56,562.

To all whom it may concern:

Be it known that I, MARION E. WATTS, a citizen of the United States, residing at Portland, in the county of Multnomah and 5 State of Oregon, have invented a new and useful Excavator, of which the following is a specification.

The present invention appertains to excavators, and aims to provide a novel and improved machine of that character for doing 10 excavation work for building foundations, for making railroad cuts, and the like.

The object of the invention is the provision of an excavator having a dirt elevator mounted in a novel manner, whereby 15 said elevator can not only be raised and lowered, but can also be swung to one side or the other, so that a relatively wide cut (wider than the tractor of the excavator) 20 can be made without running the tractor out of a straight line, the machine also embodying several improved features of construction to enhance the utility and efficiency thereof.

With the foregoing and other objects in view which will appear as the description proceeds, the invention resides in the combination and arrangement of parts and in the details of construction hereinafter described 25 and claimed, it being understood that changes in the precise embodiment of the invention herein disclosed can be made within the scope of what is claimed without departing from the spirit of the invention.

The invention is illustrated, more or less diagrammatically, in the accompanying drawings, wherein:

Figure 1 is a plan view of the excavator. Fig. 2 is a side elevation thereof. Fig. 3 is 40 an enlarged front end view of the machine, portions being broken away. Fig. 4 is an enlarged vertical section of the machine taken on the line 4—4 of Fig. 2. Fig. 5 is an enlarged fragmental plan view of a portion 45 of the driving mechanism of the tractor. Fig. 6 is a sectional view on the line 6—6 of Fig. 5. Fig. 7 is an enlarged sectional view of the friction cones and the means for adjusting the same.

The excavating mechanism is carried by a suitable tractor, which may be of ordinary construction, the same embodying suitable means for supporting the various parts of the mechanism, and the shell of the boiler 55 is extended at its forward end to accommodate the parts of the excavating mecha-

nism. The various devices are distributed, so that there is no undue strain upon any part of the shell of the boiler. The boiler 1 is mounted upon a rear driving axle 2 60 having the tractor wheels 3 secured thereto, and the front axle 4 is connected by a fifth wheel 5 with the shell of the boiler, the front or steering wheels 6 being journaled upon the front axle 4. A suitable steering gear 65 7 is connected to the axle 4 for angling or swinging the same, for purpose of steering, and the steering gear includes a hand wheel 8 whereby the tractor can be steered as usual. 70

The tractor carries a steam engine 9 which has its connecting rod 10 connected to a crank wheel 11 keyed upon one end of a transverse shaft 12 journaled for rotation upon the boiler, the operation of the steam 75 engine being controlled in the usual manner. This shaft 12 constitutes the driving shaft.

In order to propel the tractor forwardly slowly during the operation of the excavating mechanism, a pair of friction cones 13 80 are mounted upon the shaft 12, both of said cones being keyed or made fast to the shaft. A longitudinal shaft 14 journaled for rotation upon the boiler has a sleeve 15 feathered thereon at that end adjacent the cones 85 13, and the sleeve 15 carries a rigid friction cone 16 disposed between the cones 13. The sleeve 15 is operated by a lever 17 whereby the cone 16 can be forced against one or the other of the cones 13, so as to be 90 properly rotated by the shaft 12, or the cone 16 may be withdrawn slightly to release it from the cones 13 when it is desired to disconnect the shaft 14 from the shaft 12. The shaft 14 is shiftable transversely slightly, so that the cone 16 can be 95 brought into engagement with either of the cones 13. A gear wheel 18 is secured to the other end of the shaft 14 and meshes with a gear wheel 19 secured upon the corresponding end of the longitudinal shaft 20 parallel with the shaft 14 and carried in any suitable manner by the tractor. A worm 21 is secured upon the other end of the shaft 20 and meshes with a worm wheel 22 mounted 105 loosely upon a short shaft 23 journaled through brackets 24 attached to the boiler. The worm wheel 22 has a clutch hub 25 110 co-operable with a clutch member 26 feathered upon the shaft 23, and the clutch member 26 is operated by means of a lever 27, whereby the clutch member can be brought

into and out of engagement with the clutch hub 25. A gear wheel 28 is keyed upon the shaft 23 adjacent the worm wheel 22, and meshes with a gear wheel 29 mounted loosely upon the shaft 12. The gear wheel 29 in turn meshes with a gear wheel 30, which meshes with a gear wheel 31 secured upon a transverse shaft 32 journaled below the boiler immediately in front of the tractor wheels 3. A pair of gear wheels 33 are secured upon the shaft 32 and mesh with gear wheels 34 attached to the tractor wheels 3. When the friction cone 16 is forced between the friction cones 13, with the clutch member 26 engaging the clutch hub 25 of the worm wheel 22, the rotation of the shaft 12 will be transmitted by means of the gearing to the tractor wheels 3 for propelling the machine slowly forward.

The gear wheel 29 is provided with a clutch hub 29^a co-operable with a clutch member 29^b feathered upon the shaft 12 whereby the clutch member 26 and cone 16-25 are released, the clutch member 29^b can be thrown into engagement with the clutch hub 29^a, so that the shaft 12 will be connected directly to the gear wheel 29 for rotating the tractor wheels faster when the tractor is traveling on the road with the excavating mechanism idle. Any suitable means may be employed for shifting the clutch member 29^b.

The excavating mechanism includes a pedestal or short mast 35 mounted for rotation upon a bearing 36 carried by the forward end of the boiler shell, and the dirt elevator is carried by the pedestal. A transverse shaft 37 is journaled through the pedestal, and the elevator frame comprising bars 38 has one end pivotally engaging the shaft 37 within the pedestal, the upper terminals of the bars 38 being bent angularly, as clearly apparent by reference to Fig. 2. Short transverse shafts 39 are journaled through the bars 38 adjacent the upper and lower ends thereof, said bars being normally inclined, and sprocket wheels 40 are keyed upon the shafts 39. Endless sprocket chains 41, constituting an endless elevator belt, are trained around the sprocket wheels 40, and buckets 42 are carried by certain links of the chains 41. These buckets are flared so that their sides or ends project beyond the bars or side members 38 of the elevator frame, so that the cut made by the buckets will be sufficiently wide to accommodate the elevator frame.

60 The elevator belt is operatively connected with the shaft 37, and to this end, the sprocket wheels 43 are keyed upon that shaft 39 adjacent the upper end of the elevator frame, and endless sprocket chains 44 are passed around the sprocket wheels 43

and around sprocket wheels 45 keyed upon the ends of the shaft 37 at the sides of the pedestal. The shaft 37 is operatively connected with the driving shaft 12, and to this end, the bevel gear 46 keyed upon the shaft 37 meshes with a bevel gear 47 keyed upon the upper end of a vertical shaft 48 journaled for rotation within the pedestal axially thereof. A bevel gear 49 is keyed to the lower end of the shaft 48 and meshes with a bevel gear 50 keyed upon a transverse shaft 51 journaled through the forward extended end of the boiler shell below the bearing 36. A pulley wheel 52 is mounted loosely upon one protruding end of the shaft 51, and is connected by a belt 53 with a pulley wheel 54 keyed upon the driving shaft 12 adjacent the gear wheel 29. The pulley wheel 52 has a clutch hub 55 co-operable with a clutch member 56 feathered upon the shaft 51, the clutch member 56 being operated by a lever 57 which is linked to a hand lever 58 whereby the hand lever 58 may be employed for shifting the clutch member 56 into and out of engagement with the clutch hub 55 to start and stop the operation of the dirt elevator. Then the clutch member 56 is moved into engagement with the clutch hub 55, the shaft 51 is rotated with the pulley wheel 52, and this motion is transmitted to the elevator belt as will be apparent. The shaft 48 being disposed axially of the pedestal, enables the pedestal to rotate without breaking or interfering with the connection between the shaft 51 and the elevator belt.

The means for raising and lowering the elevator embodies a loop-shaped boom 59 through which the elevator extends, and having its lower end fulcrumed or pivoted, as at 60, to the pivot of the front axle 4 coaxially with the fifth wheel 5 and pedestal 35. The upper end of the boom 59 is connected rigidly by a bar 61 with the upper end of the pedestal, the boom being inclined in a direction opposite to the inclination of the elevator. A bail 62 is connected to the elevator frame near the free or lower end thereof, and a cable or flexible element 63 is connected to the bail 62 and passes over the pulley wheel 64 carried by the upper end of the boom 59, and a pulley wheel 65 carried by the upper end of the pedestal. From the pulley wheel 65, the cable 63 extends to and is wound upon a drum 66 mounted upon the operator's platform 67 which is secured upon the boiler. The drum 66 is operatively connected with a shaft 68 journaled upon the boiler. A sleeve 69 is feathered upon the shaft 68 and carries a friction cone 70 opposite the cone 16 and movable between the cones 13, the sleeve 69 being shifted by a hand lever 71, whereby the shaft 68 can be connected with the driving shaft 12, the same as the shaft 14. The

drum 66 can thus be operated mechanically for winding up or unwinding the cable 63 to raise or lower the elevator.

As a means for rotating or turning the pedestal to swing the elevator and its boom 59 to one side or the other, the lower portion of the pedestal is provided with a mutilated worm wheel 72 meshing with a worm 73 secured upon a short shaft 74 journaled upon the boiler, and a gear wheel 75 keyed upon the shaft 74 meshes with a smaller gear wheel 76 keyed upon a shaft 77 journaled upon the platform 67. A friction cone 78 is feathered upon the shaft 77 15 and is disposed between a pair of cones 78^a carried by the driving shaft 12, the cone 78 being controlled by a hand lever 79 whereby the cone 78 can be moved into and out of engagement with either cone 78^a. When the cone 78 is brought into engagement with one cone 78^a, the worm 73 is rotated in one direction for turning the pedestal correspondingly, and when the cone 78 is engaged with the other cone 78^a, the pedestal will be 20 rotated in the opposite direction. Thus by operating the hand lever 79, the pedestal may be turned properly for swinging the elevator through an arc of about 180 degrees.

30 The excavating mechanism also includes a conveyer for conveying the dirt discharged from the buckets 42 to one side, and to this end a conveyer frame 80 has one end pivotally engaging a short longitudinal shaft 81 35 carried by a bracket 82 attached to the forward end of the boiler shell. A roller 83 is carried by the shaft 81, and a roller 85 is carried by a shaft 84 applied to the free end of the conveyer frame 80. An endless conveyer belt 86 passes around the rollers 83-85. The conveyer belt 86 is operated by means of a sprocket wheel 87 keyed upon the shaft 81 and connected by an endless sprocket chain 88 with a sprocket wheel 89 45 keyed upon a short horizontal shaft 90 journaled at one side of the boiler. A bevel gear 91 is keyed upon the shaft 90 and meshes with a bevel gear 92 secured to the lower end of a vertical shaft 93 journaled at the 50 side of the boiler. A bevel gear 94 is secured to the upper end of the shaft 93 and meshes with a bevel gear 95 keyed upon that end of the shaft 51 opposite the pulley wheel 52. Whenever the shaft 51 is rotated 55 for actuating the elevator, the shaft 81 of the conveyer will be rotated for actuating the conveyer belt, the upper run of the conveyer belt moving outwardly while the upper run of the elevator belt moves upwardly.

60 As a means for raising and lowering the free end of the conveyer, an inclined boom 96 is pivoted, as at 97, to one side of the boiler, and the free end of the boom 96 is

connected by a cable, rod, or the like, 98, to a bail 99 attached to the shaft 84. A flexible member 100 connects the free end of the boom 96 and the respective side of the boiler, to limit the swinging movement of the boom properly, and the free end of the boom is connected by a block and tackle 101 with the upper end of the pedestal 35 whereby the boom 96 can be raised and lowered for correspondingly adjusting the conveyer. The end of the rope 102 of the block and tackle extends to the platform 67 so that the operator can readily adjust the conveyer.

A hopper 103 is carried by the forward end of the boiler shell below the upper end of the elevator belt, to catch the dirt discharged from the buckets 42, and to direct 80 the dirt onto the inner end of the conveyer, whereby the dirt is carried to one side by the conveyer, to be caught in a wagon at one side of the excavator, or the dirt may be discharged at one side in a pile or embankment.

The cardinal feature of the invention resides in the peculiar mounting of the elevator, whereby the elevator can not only be raised and lowered during the excavating 90 operation, but can also be swung to one side or the other, so that a relatively wide cut can be made without moving the tractor side-wise. The cut made is wider than the tractor, so that the tractor can proceed into the 95 cut, and this allows wagons, wheel barrows, or the like, being drawn into the cut at one side of the tractor to receive the dirt from the conveyer.

The invention also has other salient features which will be apparent from the foregoing, taken in connection with the drawings.

Having thus described the invention, what is claimed as new is:

An excavating machine embodying a boiler, a steering axle supporting it and having ground wheels, a rotatable pedestal supported upon the boiler to rotate about the same vertical axis as the axle, an inclined elevator frame having its upper end pivotally connected to the pedestal, an endless elevator belt carried by said frame and having buckets, an inclined boom having its lower end connected to the pivot of the axle, and means connecting the free end of the boom, pedestal and elevator frame for raising and lowering the latter.

In testimony that I claim the foregoing as my own, I have hereto affixed my signature 120 in the presence of two witnesses.

MARION E. WATTS.
